UNITED STATES PATENT OFFICE.

CHARLES S. SHALLENBERGER, OF ST. LOUIS, MISSOURI, ASSIGNOR TO COMMONWEALTH STEEL COMPANY, OF ST. LOUIS, MISSOURI, A CORPORATION OF NEW JERSEY.

DRAW-BAR CARRIER.

1,072,659.

Specification of Letters Patent. Patented Sept. 9, 1913.

Application filed August 26, 1912. Serial No. 717,048.

To all whom it may concern:

Be it known that I, CHARLES S. SHALLENBERGER, a citizen of the United States, residing at St. Louis, Missouri, have invented 5 a certain new and useful Improvement in Draw-Bar Carriers, of which the following is a full, clear, and exact description, such as will enable others skilled in the art to which it appertains to make and use the 10 same, reference being had to the accompanying drawings, forming part of this specification, in which—

Figure 1 is a front elevational view of a draw-bar carrier of my improved construction showing the supported draw-bar in section. Fig. 2 is an end elevation of the carrier. Fig. 3 is a vertical section taken approximately on the line 3—3 of Fig. 2. Fig. 4 is an enlarged detail section taken on the 20 line 4—4 of Fig. 1. Fig. 5 is a perspective view of the reversible carry iron forming a part of my invention.

My invention relates to new and useful improvements in carriers for the draw-bars 25 of car couplers, the principal object of my invention being to provide a comparatively simple, inexpensive carrier that is constructed so as to permit the carried draw-bar to swing laterally to relieve said draw-bar of lateral strains while the car is rounding a curve, and which carrier is self-centering in that it returns the draw-bar to a central position after said draw-bar has been shifted laterally in either direction.

30 A further object of my improved invention is to combine with a self-centering carrier a reversible carry iron which may be readily adjusted upon its swinging supports so as to vary the height of the carried draw-bar.

A still further object of my invention is to provide a laterally swinging, self-centering carrier having a minimum number of parts which can be easily assembled or taken apart, and further to connect the carry iron to the swinging supports of the carrier so that said carry iron can be easily and quickly detached to permit the removal of the draw-bar.

50 To the above purposes my invention consists in certain novel features of construction and arrangement of parts hereinafter more fully described and claimed.

Referring by numerals to the accompanying drawings, 1 designates the end sill of

a car underframe, and fixed thereto in any suitable manner is a plate 2, and formed on or fixed to said plate is a horizontally disposed housing 3, the front wall of which constitutes the striking plate. The end 60 portions of the front wall of this housing are extended downward and outward as designated by 4, and formed on the inner faces of these downwardly extended portions and with the opposite portions of the plate 2 are 65 lugs 5 which are arranged in pairs, and provided in their tops with trunnion seats 6. Journaled in these trunnion seats 6 are trunnions 7 that are formed on or fixed to the upper portions of lugs or hangers 8, the 70 upper ends of which are provided with heads 9 that occupy positions at the ends of the opening through the housing 3. These heads 9 bear directly against follower blocks which fit loosely in the end portions of the 75 chamber within the housing 3, and interposed between these follower blocks is a compression spring 11.

Formed on or fixed to the inner faces of the links or hangers 8 are inwardly projecting lugs 12 which are adapted to engage directly against the side faces of the draw-bar A, as shown in Fig. 1. The lower ends of the links or hangers 8 are bifurcated to form pairs of legs 13, and formed on the inner faces of the legs of one of said links or hangers are trunnion seats 14. Journaled in these seats are trunnions 15 which are formed on or fixed to a carry iron 16, and formed through the opposite end of this 90 carry iron is an aperture 17 which receives a pin 18, which latter also passes through suitable apertures formed in the lower ends of the legs of the corresponding link or hanger 8. When this pin 18 is removed the 95 carry iron swings downward upon its trunnions 15, thereby permitting the insertion or removal of the draw-bar.

The carry iron 16 is provided with a pair of oppositely disposed draw-bar-engaging 100 faces, one of which is located closer to the axes of the trunnions 15 and pin 18 than the other, and thus by reversing or turning the carry iron upside-down the height at which the draw-bar is supported can be changed. 105

When my improved draw-bar carrier is in use the draw-bar is held in a central position as shown in Fig. 1 by reason of an equal pressure of the spring 11 against the follower blocks 10 that bear directly against 110

the heads 9 of the links or hangers 8. The draw-bar thus supported is free to move laterally for a limited distance in either direction, which movement takes place as the

5 cars are rounding a curve, and when the side strain upon the draw-bar is relieved the pressure of the spring 11 exerted on the heads 9 restores the same to their normal positions, thereby moving the draw-bar to its
10 normal center position.

When it is desired to adjust the height at which the draw-bar is carried the pin 18 is removed to permit the carry iron 16 to swing downward from its position beneath the draw-bar, and said carry iron is now lifted so as to disengage the trunnions 15 from the seats 14. The carry iron is now turned upside-down, the trunnions 15 are reengaged in the seats 14, and said carry iron is now
20 swung upward into horizontal position and locked to the corresponding link or hanger 8 by means of the pin 18.

The wall of the plate 2 immediately to the rear of the housing 3 is cut away to permit the insertion or removal of the spring 11 and follower blocks 10, and when the parts of the carrier are assembled said spring is inserted through the openings to the rear of the housing 3 while under compression, thus permitting the trunnions 7 of the links or hangers 8 to be positioned in their respective seats, and as the spring-compressing means is removable the follower blocks 10 move into engagement with the heads 9.
35 When the spring is properly positioned within the housing 3 it is thoroughly protected against blows from parts exterior of the carrier, and said spring exerts equal pressure against the upper ends of the links 8.

A draw-bar carrier of my improved construction is comparatively simple, comprises a minimum number of parts which can be readily assembled or taken apart, automatically centers the draw-bar after the same has shifted laterally in either direction, and said carrier is provided with a carry iron which can be readily reversed or turned upside-down to vary the height at which the draw-bar is carried.

It will be readily understood that minor changes in the size, form and construction of the various parts of my improved draw-bar carry iron can be made and substituted
55 for those herein shown and described with-

out departing from the spirit of my invention, the scope of which is set forth in the appended claims.

I claim:

1. In a draw-bar carrier, the combination 60 with a support, of a pair of laterally swinging hangers, a draw-bar carry iron arranged between the lower portions of said hangers, and a single yielding pressure element between the upper portions of said hangers. 65

2. In a draw-bar carrier, the combination with a support, of a pair of hangers pivotally mounted on said support, a draw-bar carry iron carried by the lower portions of said hangers, and a single yielding pressure 70 element arranged between the hangers above their points of pivotal connection with the support.

3. In a draw-bar carrier, the combination with a support, of a pair of hangers pivotally connected to and depending from the support, a draw-bar carry iron carried by the lower portions of said hangers, and yielding pressure means interposed between the upper ends of the hangers for yieldingly resisting transverse swinging movement thereof. 75 80

4. In a draw-bar carrier, the combination with a pair of pivotally supported hangers, of yielding pressure means between said 85 hangers above the points of their pivotal support, and a reversible carry iron removably connected to the lower portions of said hangers.

5. The combination with a support, of a 90 pair of hangers pivotally connected to said support, heads on the upper ends of said hangers, a yielding pressure element interposed between said heads, and a carry iron removably connected to the lower portions 95 of said hangers.

6. The combination with a support having a housing, of a pair of hangers pivotally mounted on the support, a yielding pressure element within the housing between the upper portions of the hangers, and a draw bar supporting member connected to the lower portions of said hangers. 100

In testimony whereof I hereunto affix my signature in the presence of two witnesses, 105 this 13th day of August, 1912.

CHARLES S. SHALLENBERGER.
